United States Patent

Des. 237,212
Patented Oct. 14, 1975

237,212

MICROSCOPE STAND

Joseph G. Stumpf, Fairfield, and William P. Haynes,
Bridgeport, Conn., assignors to Frigtronics of Conn.,
Inc., Shelton, Conn.

Filed Oct. 12, 1973, Ser. No. 406,026

Term of patent 14 years

Int. Cl. D16—06

U.S. Cl. D57—1 E

Fig. 1.

FIG. 1 is a perspective view of the microscope stand of the invention in its folded position;

FIG. 2 is a top plan view, the microscope stand being shown in its partially extended position;

FIG. 3 is a side elevational view;

FIG. 4 is an elevational view taken from the left of FIG. 3;

FIG. 5 is an elevational view taken from the right of FIG. 3; and

FIG. 6 is a bottom plan view.

We claim:

The ornamental design for a microscope stand, as shown.
